UNITED STATES PATENT OFFICE.

GIUSEPPE PALOMBO, OF SOUTH GREENSBURG, PENNSYLVANIA.

DESIGN FOR AN ADJUSTABLE SPADE.

52,583.

Specification for Design.

Patented Oct. 15, 1918.

Application filed November 10, 1917. Serial No. 201,390. Term of patent 7 years.

To all whom it may concern:

Be it known that I, GIUSEPPE PALOMBO, a citizen of Italy, residing at South Greensburg, in the county of Westmoreland and State of Pennsylvania, have invented a new, original, and ornamental Design for Adjustable Spades, of which the following is a specification, reference being had to the accompanying drawing, forming a part thereof.

The figure is a perspective view of an adjustable spade, showing my new design.

I claim:

The ornamental design for an adjustable spade, as shown.

GIUSEPPE PALOMBO.

Witnesses:

NICHOLAS LONG,
ATTILIO PALOMBO.
